UNITED STATES PATENT OFFICE.

WILLIAM W. BURNS, OF GOVERNOR'S ISLAND, NEW YORK, ASSIGNOR TO BAILEY, BANKS & BIDDLE, OF PHILADELPHIA, PENNSYLVANIA.

DESIGN FOR A BUTTON-HOLE DECORATION.

SPECIFICATION forming part of Design No. 18,880, dated January 29, 1889.

Application filed November 30, 1888. Serial No. 292,332. Term of patent 14 years.

To all whom it may concern:

Be it known that I, WILLIAM W. BURNS, a citizen of the United States, and a resident of Governor's Island, New York, have invented

5 a new and original Design for a Button-Hole Decoration, of which the following is a specification.

My design for a button-hole decoration is fully illustrated in the accompanying drawings, in which—

10 Figure 1 is a perspective view of the decoration, and Fig. 2 is a side view. Both these views are drawn to an enlarged scale.

The design consists, essentially, of the head 15 portion A, shank B, and enlarged base D. The head A is globular in form. On the head

A is a series of annular bands, and at the top of the decoration is a convex disk, the whole forming an emblematic button-hole decoration.

20

I claim—

The design for a button-hole decoration, substantially as described, and as shown in and by the accompanying drawings.

In testimony whereof I have signed my name 25 to this specification in the presence of two subscribing witnesses.

WM. W. BURNS.
